US0D1056955S

(12) **United States Design Patent** (10) **Patent No.:** **US D1,056,955 S**
(45) **Date of Patent:** **** Jan. 7, 2025**

(54) **AUDIO PROCESSOR**

(71) Applicant: **Focusrite Audio Engineering Limited**,
High Wycombe (GB)

(72) Inventors: **Peter Phillips**, Milford-on-Sea (GB);
Joshua Luke Wilkinson, Aylesbury (GB); **Iain James Horrocks**, Southsea (GB); **Ryan Gray**, Hazlemere (GB)

(73) Assignee: **Focusrite Audio Engineering Limited**,
High Wycombe (GB)

(**) Term: **15 Years**

(21) Appl. No.: **29/719,272**

(22) Filed: **Jan. 2, 2020**

(30) **Foreign Application Priority Data**

Dennis S. Schell

(57) **CLAIM**

The ornamental design for an audio processor as shown and described.

DESCRIPTION

FIG. 1 is a top perspective view of an audio processor, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and,

FIG. 7 is a left-side elevational view thereof.

The broken lines in the drawings are provided for the purpose of illustrating portions of the audio processor that form no part of the claimed design.

1 Claim, 5 Drawing Sheets
